INVENTOR,

Ralph G. Whitlock
By G. Sharpen

HIS ATTORNEY

UNITED STATES PATENT OFFICE.

RALPH G. WHITLOCK, OF LOS ANGELES, CALIFORNIA.

LOOSE-LEAF BOOK.

1,300,206.

Specification of Letters Patent.

Patented Apr. 8, 1919.

Application filed August 21, 1918 Serial No. 250,885.

To all whom it may concern:

Be it known that I, RALPH G. WHITLOCK, a citizen of the United States, residing at the city of Los Angeles, State of California, have invented new and useful Improvements in Loose-Leaf Books, of which the following is a specification.

My invention relates to the construction of the metal portions of the cover or case, which for distinction I call the back frame, and the object thereof is to cheapen the construction of such portions and to provide simple means for opening and closing the ring members.

15 In the drawings forming a part of this application:

Figure 1 is a top plan of the back frame.

Fig. 2 is an enlarged section on the line 2—2 of Fig. 1, but showing the rings open.

20 Fig. 3 is an enlarged section on the line 3—3 of Fig. 1, but with the rings open.

Fig. 4 is a detail on the line 4—4 of Fig. 1.

Fig. 4^a is a plan of a piece of metal before being bent to form an attaching plate.

25 Referring to the drawings 5 is a piece of sheet metal, preferably of mild steel, which forms the back member and is preferably slightly curved. Near each end for a portion of its width the back member is trans-

30 versely cut and the portion between the cuts is pressed upwardly and forms attaching loops 6. This back member is bound in the cover, not shown. The ring member is composed of side members 7 and 8, which are

35 preferably of heavy wire, the ends of which are turned and riveted together as shown in Fig. 1. Half ring members 9 and 10 are secured to the side members in pairs which register. There may be two or more pairs

40 of half ring members. I have shown three pairs in the drawings. These half ring members pass through slots 12 in the ends of the attaching plates 13 except the central pair which pass through a hinge. The ends of these attaching plates are bent downwardly and then inwardly as best shown in

45 Fig. 2 and form pockets in which the side members are received. These plates have narrow portions on the sides which are bent downwardly on the dotted lines 14 at right angles to the top and again bent at right angles on the lines 15 and form attaching

50 lugs 16, the inturned ends of which project under the loops of the back member as best shown in Figs. 2 and 4 and attach the ring

member to the back member. It will be understood that before attaching the ring member to the back member these lugs have their inturned ends separated far enough to straddle the loops of the back member and when 60 positioned the lugs are pinched to position their inturned ends under the loops as best shown in Fig. 4. At one end I mount on the side members an opening and closing and locking device which consists of a lever 65 17 which is rockably mounted on member 8. A link 18 is rockably mounted on member 7 and is connected to lever 17 by a rivet 19 at a point which is a little below the plane which passes through the centers of members 7 and 8 when the rings are closed and which point is close to member 8 as best shown in Fig. 3. In the center of the side members I may connect them together by a hinge as shown in Fig. 1. The members 75 forming the hinge are rigidly secured to the side members. This hinge gives a little better bracing to the central portions but can be omitted where cheapness of construction is desired. It will be observed that lugs 16 80 limit the inward movement of the side members and prevent them from coming out of the pockets. Where a cover is not desired the back plate may be omitted.

Having described my invention I claim:

1. In a loose leaf book, a back plate comprising a strip of metal having loops struck up therefrom; in combination with a ring member comprising side members carrying half ring members; means to connect said side members, said connecting means permitting said side members to rock and move back and forth laterally and having lugs adapted to engage the loops of the back plate; and means to rock said side members 95 and move them laterally.

2. In a loose leaf book a ring member comprising transverse attaching plates having downwardly projecting lugs whose ends are turned inwardly to form pockets; side members hingedly connected at their ends mounted for sliding movement in said pockets;

half ring members secured to said side members; a lever loosely mounted on one of said side members; and a link loosely mounted 100 on the other of said side members, an end of said link being hingedly connected to said lever at such point that when the half ring members are closed the rivet connecting the link to the lever is below the plane pass-

105

110

ing through the centers of the side members, whereby the half ring members are locked closed.

3. In a loose leaf book, a ring member comprising transverse attaching plates having downwardly projecting lugs and having pockets at the ends thereof; side members hingedly connected at their ends mounted in the pockets of said attaching plates; means connected to said side members to move said side members laterally and to rock them; and half ring members arranged in pairs and secured to said side members.

4. In a loose leaf book, a ring member comprising transverse attaching plates having downwardly projecting lugs and having

pockets at the ends thereof; side members hingedly connected at their ends mounted in the pockets of said attaching plates; means connected to said side members to move said side members laterally and to rock them; and half ring members arranged in pairs and secured to said side members; in combination with a back plate adapted to be bound in the cover, said plate having loops in which the lugs of the ring member are received, whereby the ring member is attached to the back plate.

In witness that I claim the foregoing I have hereunto subscribed my name this 14th day of August, 1918.

RALPH G. WHITLOCK.
